[57] **CLAIM**

The ornamental design for a face filter mask, as shown and described.

DESCRIPTION

FIG. 1 is a perspective view of a face filter mask, showing my new design;

FIG. 2 is a front elevational view thereof;

FIG. 3 is a side elevational view thereof;

FIG. 4 is a top plan view thereof;

FIG. 5 is a perspective view of a second embodiment of the face filter mask;

FIG. 6 is a top plan view thereof; and,

FIG. 7 is a side elevational view thereof;

FIG. 8 is a rear elevational view of FIGS. 1-4, with the straps partially cut away; and,

FIG. 9 is a rear elevational view of FIGS. 5-7, with the straps partially cut away.

The broken line showing of the face of a wearer is for illustrative purposes only and forms no part of the claimed design.
